ABSTRACT

A regulator for the optimal ventilation of any enclosed space, comprising an air passage formed in an annular casing, a portion of which passage, at one end of the annulus, is closed by a partition, the other portion of which passage is sealable by means of a control valve in the shape of a disc having through passages, the disc being coaxial with the casing and rotatably mounted therein, the ventilation being effected by making use of the difference in air pressure on both sides of the passage.

VENTILATION REGULATING DEVICE

This application is a continuation-in-part of application Ser. No. 65,309, filed Aug. 19, 1970, now abandoned, which is a continuation of application Ser. No. 783,939, filed Dec. 16, 1968, now abandoned.

BACKGROUND OF THE INVENTION

The present invention relates to a ventilation regulator of the type comprising an air passage formed in an annular casing, a portion of which passage at one end of the annulus being closed by a partition, the other portion being sealable by means of a disc-like element having closed sections. The remaining portion of the disc-like element consists of separated vanes or blades. The disc-like element is coaxial with the casing and rotatably mounted therein.

It is an object of this invention to provide a device of this type which permits an optimal regulation, for example of the ventilation of a room or similar enclosed space, or of the passage of other fluids, by merely utilizing in the main the difference in fluid pressure on both sides of the air passage, and thereby to avoid such adverse phenomena as unduly low reactivity and more especially draught and objectionable rattling occurring in the known ventilation regulators. Yet the device according to this invention can be manufactured at low cost and does not require much room.

To this effect a ventilating device of this type according to the invention, is characterized by a control valve in the form of a circular disc capable of swinging coaxially between end stops in the casing, one half of which disc, extending over approximately 180°, is closed, said disc further comprising a plurality of sector-shaped blades, the central portions of which are turned at a slight angle relative to the plane defined by said first-mentioned disc half, the arrangement of said blades being such that their axial projections on the said plane together cover the other disc half at least substantially, there being connected to said disc adjustable means affecting the activity of the thrust of the air passing through the passage on the positions of the control valve.

Thus a minimum permissible construction depth in the order of a few centimeters only will be sufficient. The device readily responds to the pressure differences prevailing on both sides of the annular casing, and is widely adaptable to greatly varying working conditions. Also, in the farthest closed position of the disc, i.e., the position in which all blades of the disc are behind the division plate, as seen in axial direction of the casing, the effect of the thrust of the fluid flow, which in this position is forcedly deflected beyond the division plate in a direction transversely of the axis of the casing, on the blades turns out to be sufficient for the valve to be retained in that position.

The adjustable sealing plate allows of a simple and easy control of the passage in the annular casing according as the circumstances, and can even be used to seal off the passage completely.

According to a typical embodiment of this invention the inner winding of a helical spring can be clamped about a hub of the control valve, the outer end of which spring abuts against a stop in an accommodating space for the helical spring in a central bearing part connected with the division plate and rotatively adjustable in a bearing ring fixed to said plate and having said cen-

tral bearing part extending therethrough, and this to vary the tension of the helical spring.

By slightly turning the end of the bearing part extending through the bearing ring of the division plate, 5 the helical spring can be tensioned to a greater or less extent. As a result of the cooperation between the outer end of the helical spring and the bearing part through the intermediary of a stop, the assembly of the helical spring can be realized in a simple manner and 10 the spring can be readily brought to the desired pre-tension. Besides the helical spring can be easily replaced, if so desired.

It is a structural advantage that, according to this invention, a fixing spring secured to the division plate is 15 active upon a row of teeth at the circumference of the rotative bearing part for the control valve. In addition, the fixing mechanism is almost entirely hidden from sight behind said division plate.

According to a further embodiment of this invention, 20 the control valve may be provided, in this construction or in place of the helical spring mechanism, with a radially adjustable out-of-balance weight and with a track, spaced from the shaft of the control valve, for an out-of-balance ball enclosed within said track, and this in 25 particular when uses are concerned in which during operation the shaft is always in a horizontal position.

While the weight is easily accessible according to the 30 arrangement and the working conditions, for example from the side of the control valve away from the division plate, the ball ensures, by virtue of a suitable arrangement of the ball track, that the farthest closed position of the control valve is not a so-called dead center position.

In addition to, or possibly in place of the adjustable 35 weight, the control valve may, of course, also be effected by suitably arranged, magnetically operative provisions.

In another embodiment, there is provided a housing 40 in the shape of a ring which on one end is provided with a stationary partition closing approximately half of the passage through such housing and a control member having an open portion and a closed portion and arranged for rotation coaxially with said ring by the side of said partition.

In the first described embodiment of this invention, 45 the control member is manually adjustable, for which frictional forces have to be overcome at the point where the control member is connected with the housing. In that construction, the stationary partition is of substantially semi-circular shape. To obtain the desired passage area, the substantially semi-circular control member can be swung in full or in part behind the partition.

In this second embodiment there is a ventilator of the 50 kind described in the opening paragraph of this specification, in which the area of passage through the housing is also automatically decreased according to the overpressure prevailing at one end of the housing relative to that at the other end.

To this end, it is proposed, in such a ventilator, that 55 said control member is journalled for free rotation, is provided with inclined blades separated by slits and is connected with means exerting a force on it, the arrangement being such that the control member assumes an angular position against the action of said

force, depending on air current pressure resulting from overpressure, acting on the blades on one end of the housing, in which position the slotted portion of the control member comes to lie at least partially behind the closed partition portion.

Preferably, said force-exerting means is an out-of-balance weight accommodated in a receptacle of the control member.

There is thus produced an extremely simple, compact ventilator, which rapidly and automatically reacts to fluctuating pressure situations, and moreover, can easily and cheaply be manufactured.

The size of the out-of-balance weight can be selected to suit particular cases of use. Instead, it is also possible, with a given minimum out-of-balance weight, to add one or more additional out-of-balance weights.

According to a further elaboration of the principle according to this embodiment of the invention, the successive blades of the control member may be disposed in at least substantially overlapping relationship as viewed in axial direction, that is to say, that the projections of the slits between the successive blades, on the plane perpendicular to the axis of rotation, have a width approaching zero value.

According to an advantage of this embodiment of the invention, the control member may be subdivided into a plurality of sectors each having an equal number of blades, the successive blades of pairs of opposite sectors being interconnected by imperforate cross-walls, and the blades of the intermediate sectors having the open passage-slits formed between them.

In a preferred form of this embodiment according to the invention, the partition over the non-closed half may be constituted by at least one pair of portions extending over diametrically opposite circle sectors and each consisting of a plurality of concentric ring segments oriented at an angle to the axis of the housing.

According to a further feature of the invention, said ring-segments at diametrically opposite positions may be inclined in the same direction.

BRIEF DESCRIPTION OF THE DRAWINGS

In illustration of this invention, the embodiments will now be described, by way of example, with reference to the accompanying drawings.

FIG. 1 is a front elevation of the device, as seen from the room;

FIG. 2 is a vertical section taken along the line II—II in FIG. 1, with elevational view;

FIG. 3 is a rear elevation of the control valve;

FIG. 4 is a vertical section taken along the line IV—IV in FIG. 3, with elevational view of the control valve;

FIG. 5 is a vertical cross-sectional elevation of a ventilator according to the invention;

FIG. 6 is a view from the right in FIG. 5 of the control member;

FIG. 7 is a diagrammatic cross-sectional view on the line VII—VII of FIG. 6;

FIG. 8 is a view from the left in FIG. 5 of the housing and showing the partition.

DESCRIPTION OF THE PREFERRED EMBODIMENT

Referring to the drawings, the ventilating device mainly consists of an axially narrow, cylindrically annu-

lar plastic casing 1 having mounted thereon, at the front facing the room, a division plate 2 in the form of a lid sealing the lower half of the passage area in said casing. At the opposite end of the casing 1, there is mounted in the passage a gridiron 3. Reference numeral 4 generally stands for a substantially disc-shaped control valve. In the position shown in FIG. 1, the lower half 5 of the disc is entirely closed and the upper half consists of a plurality of sector-shaped blades 6, the central portions of which are displaced with respect to the plane defined by the lower half of the disc. The projections of the blades on the said plane are contiguous with each other without any interruption. The control valve 4 is further provided with a hub 7 which has a shaft 8 extending therethrough and so mounted therein as to be locked against rotation, one end of said shaft being mounted for rotation in a central bearing part of the gridiron 3, the other end in a separate cylindrical bearing part 9 which fits rotatively in a bearing ring 10 formed on the plate 2. Projecting from the side of the bearing ring 10 away from the room is a row of teeth 11 formed on the bearing part 9, with which teeth the suitably formed ends of the two legs of an essentially V-shaped spring 12 are in engagement, said spring being attached to the plate 2 adjacent 13. By engagement of a suitable key into three boxes 14 in the end face of the bearing part 9 coming into view, said bearing part can be rotated for the purpose as described herebelow.

Behind the row of teeth 11, the outer circumferential portion of the bearing part 9 is provided with a groove 15 accommodating the interior edge portion of a semi-circular disc-like sealing plate 16 positioned, in the condition shown in FIGS. 1 and 2, behind the plate 2. The outer circumferential edge of the sealing plate 16 is accommodated in a circular inner circumferential groove 17 of the casing, formed by a marginal recess in the inside wall of the casing 1 directly behind the plate 2. Provided about the upper half of the casing, on the side of the room, is a frame 18 with an outer circumferential groove 19. Passed through this groove is a pull cord 20 which is attached to the free end of an arm 21 fixed to the sealing plate 16 and extending, as may appear from FIG. 1, above the plate 2 and, with a hooked end portion, in front of the opening of the groove 19. By means of the cord 20, the sealing plate can be rotated from its open position, shown in FIG. 1, into the upper half of the casing, which is cleared by the plate 2, the grooves 15 and 17 functioning as guides for the plate.

The head of the bearing part 9, away from the room, has a circular space 22 for accommodating a helical spring 23, the inner winding of which is clamped about the left-hand end, as seen in FIG. 2, of the shaft 8, and the outwardly curved, hooked end of the outer winding abuts against a stop, not shown in the drawings, at the outer circumference of the accommodation 22. By rotation of the bearing part 9 by means of the said key, the outer winding of the helical spring, upon assembly, can be positioned against the stop in the accommodating space and tensioned. The pre-tension of the helical spring to be set in this way depends on the local situation and conditions under which the ventilating device must work. It will be understood that the pre-tension will act on the control valve 4 in a rotary sense opposite to a current of air acting on the blades 6 in the direction

of the arrow A (FIG. 2), so that said control valve can adjust itself rotatively about its shaft 8 according to the intensity of the air current.

Projecting from the central bearing part of the gridiron 3 into the casing is a sleeve 24 substantially enclosing the hub 7 and forming an end abutment at 25 for the stops, not shown, on the hub 7 for the two extreme positions of rotation to be occupied by the control valve 4. One of these extreme positions is the position shown in FIG. 1, the other one the position in which the valve has turned through substantially 180° and the blades 6 have arrived behind the plate 2. In this position, too, a strong air current may yet be active on the blades in the direction of the arrow A in FIG. 2, because the air current is curved down over the upper edge of the plate 2.

As may appear from FIGS. 3 and 4, the closed half of the valve is further provided with a vertical slot 27 along which an out-of-balance weight 28 for the control valve can be fixed by a clamping screw 29.

Also, provided at the bottom of the closed half 5 of the control valve is a channel-like accommodation track of a cross-sectional shape as shown in FIG. 3, and more clearly in FIG. 4. Especially in the absence of the helical spring 23 described hereinbefore, or in the case of a defective spring when the latter is actually used, a ball 31 movable in said track 30 avoids a dead center position of the valve 4.

It will be obvious that as a result of the adjustment of the sealing plate 16 by means of a cord 20, the regulation of the pre-tension exerted by the helical spring 22 on the control valve, and the adjustability of the radial distance of the weight 28 relative to the axis of the control valve by means of the set screw 29, the ventilating device according to this invention is very widely adaptable to all kinds of working conditions greatly varying in each individual case.

The embodiment shown relates to the use of the instant device in a suitable opening in a window pane or wall panel 32 (FIG. 2), the attachment being effected by means of a two-part counterframe 34 fixed by screws 33.

The device according to this invention may be typically applied to a ventilating system for a building with a vertical shaft, at the top of which a fan is operative, and with horizontal branches in the various stories and rooms.

The device according to this invention is further typically used for the self-regulation of the ventilation in vehicles.

Referring to the drawings of the second embodiment, the ventilator, generally designated by reference numeral 36 in FIG. 5, consists essentially of a housing having an annular outer peripheral wall 37, with a partition 38 therein on one end thereof, said partition being integral with the wall 37, a hollow pin 39 extending into the housing from the center of the partition, as well as a control member 40 which, essentially consisting of a plurality of blades 41, has the form of a fan; fixed with a snap connection in a hub 42 on the control member 40 is a loose sleeve 43. This sleeve 43 forms together with a bushing 44, inserted in it in reverse position, a cavity accommodating two series of balls 45 and 46, by means of which the control member is freely rotatable on a ball bushing 47 mounted on the hollow pin 39 formed on the partition.

The rotation of the control member is limited to 180°, namely, 90° to the left and to the right from the position shown in FIGS. 5, 6 and 8, owing to the dog 48 extending from the sleeve 43 having an abutment 5 against two stops 49 extending from the partition 38 at some distance from the hollow pin, as shown in broken lines in FIGS. 5 and 8.

The partition 38 consists of alternating entirely closed circle quadrants 50 and upper and lower quadrants 51, each constituted by a plurality of concentric ring segments inclined outwardly and downwardly and having a cross-sectional configuration as shown in FIG. 8.

FIGS. 6 and 7 illustrate the construction of the fan-shaped control member: the sector-shaped blades which, relative to the plane perpendicular to the axis X—X of the ventilator 36, are inclined about a radius, as shown in FIG. 7, define successive passage slits 52 between them over the quadrants, which in the position 15 of the control member 40 correspond with the ring segment quadrants 51 of the partition 38. The other sector-shaped blades 41, i.e., in the quadrants of the control member corresponding with the closed quadrants 20 of the partition in the position shown, are successively interconnected by imperforate crosswalls 53.

The control member assumes a position as shown under the influence of an out-of-balance weight 54 accommodated in a receptacle 55 of the control member, 25 said weight taking the form of a pin which is a clamping fit in receptacle 55. If so desired, this pin 54 may be replaced by a lighter or heavier one, according to the contemplated functioning in the particular case in which the ventilator is used. In the case of a pressure difference on opposite ends of the ventilator 36, a current of air moves through the slits between the ring segment of the partition, impinges on the blades 41 of the control member, and rotates the latter against the action of the out-of-balance weight constituted by the pin 30 54 until a position of equilibrium is assumed, in which the control member 40 is at least partly swung with its slotted quadrants behind the imperforate quadrants of the partition. The direction of rotation is determined by the end of the housing at which overpressure prevails 35 relative to the opposite end, which means that the device assumes a more active throttle position in the case of both overpressure on the inside and on the outside, and according to the magnitude of such overpressure.

A particular advantage is the simple construction and assembly from a small number of parts of the ventilator. The device may be mounted in a panel or glass pane by means of a groove formed at the circumference of peripheral wall 37 between circumferential ribs, using a suitable packing of suitable rubber or plastics material.

It will be clear that, within the framework of the invention, various other embodiments and solutions relative to the exemplary embodiment described above and shown in the drawings are possible in numerous points. In particular, instead of four quadrants, other numbers of sectors may be used.

I claim:

1. A ventilation regulating device comprising an air passage formed in an annular casing, one half of said passage at one end of the annulus being closed by a division plate extending over approximately 180°, the

other half being sealable by means of a substantially semi-circular disc-like sealing plate in a transverse plane beside said division plate, said sealing plate being coaxial with said casing and rotatably mounted therein, characterized by a control valve in the form of a circular disc capable of swinging coaxially between end stops in the casing, one half of which disc, extending over approximately 180°, is closed, said disc further comprising a plurality of sector-shaped blades, the central portions of which are turned at a slight angle relative to the plane defined by said first-mentioned disc half, the arrangement of said blades being such that their axial projections on the said plane together cover the other disc half at least substantially, there being connected to said disc adjustable means affecting the activity of the thrust of the air passing through the passage on the positions of the control valve.

2. A device as claimed in claim 1, wherein the inner winding of a helical spring is clamped about a hub of the control valve, the outer end of which spring abuts against a stop in an accommodating space for the helical spring in a central bearing part connected with the division plate and rotatively adjustable in a bearing ring fixed to said plate and having said central bearing part extending therethrough, and this to vary the tension of 25 the helical spring.

3. A device as claimed in claim 2, wherein a fixing spring secured to the division plate is active upon a row of teeth at the circumference of the rotative bearing part.

4. A device as claimed in claim 1 wherein the control valve is provided with a radially adjustable out-of-balance weight and with a track, spaced from the shaft of the control valve, for an out-of-balance ball enclosed within said track.

5. A ventilator comprising a first disc fixable to a wall, a control member including a second disc coaxially rotatably supported by said first disc, said discs each having an axially slotted area and an axially closed surface area, said slotted and closed surface areas forming respective slotted and closed sectors circum-

ferentially alternatingly and substantially equally divided, said second disc being rotatable with respect to said first disc between a first position and a second position, in said first position each slotted sector of said second disc being axially substantially coincident with a slotted sector of said first disc, in said second position each slotted sector of said second disc being axially substantially coincident with a closed sector of said first disc, said slotted area of said second disc being provided with spaced inclined vanes extending radially with respect to the axis of rotation, on rotation of said second disc in one direction of rotation the leading radial edges of said vanes moving axially spaced from but close to said first disc and on rotation in said one direction of rotation the trailing edges of said vanes moving axially further spaced from said first disc, and return means being provided to bias said second disc to said first position the biasing by said means increasing on rotation of said second disc towards said second position.

6. A ventilator according to claim 5 characterized in that the successive control member vanes are disposed in at least substantially overlapping relationship as viewed in axial direction.

7. A ventilator according to claim 5 characterized in that the control member is subdivided into a plurality of sectors each having an equal number of vanes, the successive vanes of pairs of opposite sectors being interconnected by imperforate cross-walls, and the vanes of the intermediate sectors having the open passage-slits formed between them.

8. A ventilator according to claim 7 characterized in that a partition is provided over the non-closed half which is constituted by at least one pair of portions extending over diametrically opposite circle sectors and each consisting of a plurality of concentric ring segments oriented at an angle to the axis of the housing.

9. A ventilator according to claim 8 characterized in that the ring segments at diametrically opposite positions are inclined in the same direction.
